UNITED STATES PATENT OFFICE.

HARVEY L. KEETER, OF LIBERTY, MISSOURI.

MOLD.

Application filed September 22, 1923. Serial No. 664,227.

To all whom it may concern:

Be it known that I, HARVEY L. KEETER, a citizen of the United States, residing at Liberty, in the county of Clay and State of Missouri, have invented certain new and useful Improvements in Molds, of which the following is a specification, reference being had to the accompanying drawings.

This invention relates to improvements in molds and more particularly to a mold primarily intended for the construction of cruciform tombstones.

An important object of the invention is to provide a device of this character so constructed that the size and thickness of the concrete cross formed thereby may be readily altered or the lengths of the arms thereof changed as may be desired.

A still further object of the invention is to provide a device of this character which may be readily and cheaply produced, which will be durable and efficient in service and a general improvement in the art.

These and other objects I attain by the construction and arrangement shown in the accompanying drawings wherein for the purpose of illustration is shown a preferred embodiment of my invention and wherein:

Figure 1 is a plan view showing a mold constructed in accordance with my invention;

Figure 2 is an enlarged sectional view taken on the line 2—2 of Figure 1;

Figure 3 is a plan view showing the mold in use for forming slabs;

Figures 4, 5 and 6 are enlarged plan views of alternative end members;

Figure 7 is an enlarged detail sectional view on the line 7—7 of Figure 1;

Figure 8 shows the arrangement of a primary or mother mold preparatory to building up a cross mold of the desired thickness; and

Figure 9 is a section on the line 9—9 of Figure 8.

Referring now more particularly to the drawings, the numeral 10 indicates a support or table having a flat upper surface upon which the mold proper is arranged.

The mold consists of a section 11 for forming the vertical stem of the cross and a section 12 for forming the cross arm thereof. Each of these sections is formed of a pair of spaced side members 13 and since these side members are of similar construction

with the exception of the length thereof, but one thereof will be herein described.

Each side member proper is divided into two sections A and B arranged at opposite sides of the center of the crossing point of the main stem 11 and arm 12. Each section is formed of a lower layer 14 and an upper layer 15, the inner edges of which are oppositely beveled as at 14^a and 15^a, or otherwise shaped to provide a desired corner upon the cross and a plurality of intermediate layers 16 forming spacing elements determining the thickness of the cross. The meeting ends of the sections of the arm and main stem sections are beveled as indicated at 17 to provide a joint therebetween. Other types of joints may be provided if desired. Sections 14, 15 and 16 are secured together and to the table by means of securing elements 18 and it will be obvious that by varying the length of the sections 13 and the space between the adjacent faces thereof, the width and length of the arms of the cross may be regulated as desired.

It will be seen that the sections 13 in opposition provide with the table 10 the desired cross section of a cross formed by depositing concrete between the same. In conjunction with these sections, I provide end members 19 which are similarly in cross section to the cross section of the cross, being formed so that they interfit at their side edges with the mold sections 13 and thereby fill the space therebetween. These sections are secured in desired adjusted position in any suitable manner, screws being employed in the present illustration. Certain of these end members have both ends thereof flat. At C I have illustrated end members, both ends of which are squared, at D and end member, one end of which is square and the other end of which is formed to provide a point at the end of the cross and at E, F and G. I have illustrated end members, both ends of which are formed with different types of end surface and which are interchangeable with the blocks C and D in the formation of the cross. These end members are preferably laminated as in the construction of the sections 13 so that a desired thickness of the cross may be effected in conjunction with any desired width.

It will, of course, be understood that different widths of end members must be em-

ployed with different widths of crosses. I further provide a name plate board 20 which may be secured upon the surface of the table therein at the intersection of the 5 arms and which is provided with grooves 21 in which may be slid lettering forming dies 22 to provide upon a completed cross the name, dates and the like.

It will be seen that by adjusting the 10 widths of the arms and placing the end members in the proper position, the desired width and length may be obtained and that by placing a plate 20 in position with the desired insignia thereon, a complete cross 15 may be produced at a single operation. In the formation of the cross, if desired, reinforcing elements 23 may be introduced into the material thereof.

It will further be seen that if it is desired to produce simply a column, this may 20 be effected by simply moving the end blocks C to a point where they align with the edges of the sections 13 of the vertical member of the cross, subsequent to which by an adjustment of the end member C operating between the sections 13 of the vertical section 11 and the block D or corresponding blocks, the length of the column may be determined.

30 The method of employing the mold is best shown in Figure 8, in which figure I have shown a mold each of the side sections of which is composed of a single layer, on certain of these side sections the second 35 layer having been superimposed. It will be seen that each separate layer of itself forms a mold and that a desired number of the molds are combined to produce the desired thickness of the cross. The first layer or mold might be termed a mother mold or form since it is only necessary in assembling the completed mold to properly position this first mold. After this mold is placed the remaining mold can be placed thereon with 40 45 the bolt receiving opening thereof in alignment with the first mold and their proper positioning is assured. In many instances the production of a thin slab cross is desired and in such instances a single layer or mold 50 will often suffice.

A mold of the above character may be very cheaply produced since the elements thereof may be formed of wood and may all be formed by operations easily performed at the ordinary planing mill. Such a mold is furthermore very readily assembled and disassembled and is capable of a wide range of use impossible with the ordinary form of mold provided for this purpose. It will be observed that certain 55 60 changes and modifications may be made in the construction of the mold as hereinbefore

set forth without in any manner departing from the spirit of my invention and I accordingly do not limit myself to such specific structure except as hereinafter claimed.

What is claimed is:—

1. A mold for forming cruciform concrete structures comprising vertical and cross arm members, each formed in opposed sections 70 of laminated materials and end sections slideable between said side sections to adjust the length of the stem and cross arm, said end members interfitting with the opposed edges of the sections and thereby filling the 75 space therebetween.

2. In moulding apparatus, a support, opposed laminated sections arranged upon the support and combining therewith to produce a desired cross sectional area, each of 80 said side sections being adjustable upon the support and variable as to depth, and end members interfitting with the opposed edges of the side sections and combining therewith and with said support to form a mold 85 having an open top.

3. In moulding apparatus, a support, opposed laminated sections arranged upon the support and combining therewith to produce a desired cross sectional area, each of 90 said side sections being adjustable upon the support and variable as to depth, and end members interfitting with the opposed edges of the side sections and combining therewith and with said support to form a mold having an open top, each of said end sections 95 being laminated and having the sections thereof secured together by removable securing elements.

4. In a mold, a support, side and end sections resting thereon, each of said side sections comprising an upper section and a lower section having their inner edges formed to provide a desired corner upon the moulded structure and intermediate 100 sections of material to regulate the thickness of the formed structure, said end sections conforming along their side edges to the shaping of the opposed edges of the side sections and interfitting therewith.

5. In a mold, side sections arranged to define a cross, each of said side sections being variable as to thickness and end sections coacting with said side sections and interfitting with opposed faces thereof to 110 close the ends of the cross members, said end members being adjustable longitudinally of their respective side members whereby to adjust the length of either the vertical or cross member of the produced 120 cross.

In testimony whereof I hereunto affix my signature.

HARVEY L. KEETER.
